MANUFACTURE OF SHOES

Joseph W. Barina, Chicago, Ill., assignor of forty nine per cent to Carl A. Laystrom, Chicago, Ill.

Application September 6, 1935, Serial No. 39,393

20 Claims. (Cl. 12—7)

This invention relates to improvements in machines for lasting shoe uppers and laying soles, and its main objects are to provide an improved mechanism which simultaneously lasts the side, heel and toe portions of the upper, and which after lasting the upper supports the work in position during the laying of the sole and provides means for pressing and shaping the cemented outer-sole upon the inner sole and welt on the last, whereby these parts of the shoe are permanently assembled in the same machine by the same operator, and the usual separate sole-shaping and welt-beating machines are eliminated. Other objects of the invention will be apparent from the disclosure.

The invention consists in the matters herein-after described and claimed, and a practical embodiment of means for carrying out its various features is shown in the accompanying drawings, in which Fig. 1 is a top plan view of a lasting machine constructed in accordance with my invention with its parts in their relative positions when the wipers are spread; Fig. 2 is a similar view with the parts positioned when the wipers are closed to lasting position; Fig. 3 is a transverse vertical view taken centrally of the machine and partly in section on the line 3—3 in Fig. 2 with the wiper-shaft broken away at its front end; Fig. 4 is a longitudinal vertical view taken partly in section on the line 4—4 in Fig. 2; Fig. 4a is a detail sectional view on an enlarged scale showing the ball-joint between the wipers and their posts; Fig. 5 is a detail view of the yoke to center the side-wipers taken in vertical section on the line 5—5 in Fig. 2; Fig. 6 is a plan view of the sole of the last with the inner-sole of the shoe in place thereon and the edge of the shoe-upper in its position on the last before it is lasted thereon; Fig. 7 is a detail sectional view taken on the line 7—7 in Fig. 6 with the wipers in adjacent position; Fig. 8 is a view in elevation showing the locking means for centralizing the wiper-yoke and the operating means for the last-jack on the rear end of the machine; Fig. 9 is a detail view partly in section taken on the line 9—9 in Fig. 8; Fig. 10 is a detail view partly in section taken on the line 10—10 in Fig. 3; Fig. 11 is a diagrammatic view showing an arrangement of a pair of the present machines for lasting the uppers of a pair of shoes, and an intermediate screw-press for use in conjunction with each machine in steps of its lasting operation and also in the final step of applying the outer-soles to the lasted uppers in the machines; Fig. 12 is view in elevation of the press; Fig. 13

is a top plan view of a mold block used on the machine; Fig. 14 is sectional view of the same taken on the line 14—14 in Fig. 13; Fig. 15 is a detail cross-sectional view taken on about the line 7—7 in Fig. 6 showing the condition of the shoe when it is removed from the machine; and Fig. 16 is a detail view taken on the line 16—16 in Fig. 3.

In the drawings the reference numeral 1 indicates a shoe-last, 2 an inner-sole with its cork-lining, 3 a shoe-upper and 4 a welt stitched to the upper, all these parts being of usual construction.

The metallic supporting frame of the lasting machine comprises an opposite pair of spaced parallel angle bars 5 having upper and lower webs 6 and 7 and an intermediate rectangular baseplate 8 bolted at 9 to and projecting somewhat in the rear of the lower webs of the bars. The plate is formed with a front bearing block 10 and with a rear pair of spaced bearings 11 which support the through rods 12 on which the wiper mechanism is carried. The wipers are thin metallic plates formed to stretch or wipe the side, heel and toe portions of a shoe-upper on the last at one operation. The toe wiper is composed of sectional plates 13 and 14 curved on their inner edges to correspond with the toe of the selected last; the outer plate 13 is formed with a cross-tongue 15 which projects into an open-top cross-groove 16 in the inner or ball-plate 14, and each plate is formed with an open-top groove 17 extending rearwardly, the groove in the outer plate being directed toward its rear end slightly outwardly away from the center line of the machine and the groove in the ball-plate being directed toward its rear end slightly inwardly. The wipers shown are for the left lasts of a pair, except those at the right hand side of Fig. 11 which are for the corresponding right lasts of the pair.

The heel wiper is composed of sectional plates 18 and 19 curved on their inner edges to conform with the heel of the last; one of the plates is formed with a cross-tongue 20 which projects into an open-top cross-groove 21 in the companion plate, and each plate is formed with an open-top groove 22 extending forwardly and directed slightly inwardly toward the center of the machine. The side wipers 23 and 24 are elongated plates curved on their inner edges to conform respectively with the contour of the inner and outer sides of the shank and ball of the last and formed at their ends to slide in the grooves 17 and 22, respectively, in the toe and heel wipers.

- Each side wiper is formed with front and rear closed cam-slots 25 and 26 which correspond with the direction of the grooves in the associated sections of the heel and toe wipers, and headed bolts 27 carried by the latter hold the side wipers in place and control their movements toward and away from the last. The tongue and groove connections between the wiping parts are so proportioned and formed as to provide flush slip-joints between all working surfaces of these parts and thus afford smooth and continuous wiping surfaces on the welt and upper all around the last and ensure the work being free of any irregularities or ridges. The wipers are tapered or beveled on their lower faces toward their working edges, as shown in Fig. 5 to wipe on the curvature of the upper on the last and avoid making any opening or gap between the welt and upper along the line of their stitching.
- The wipers are supported on carriages constructed to spread them outwardly to enlarge their intermediate opening both longitudinally and laterally to receive the last and upper, and then to close them inwardly in place against the welt, and then to stretch and wipe the upper onto the last. Each section of the heel and toe wipers is supported by a movable carriage consisting of a vertical pillar 28 and an upright standard 29 bolted at its lower end to its associated pillar and flared away from the latter toward its upper end, which terminates in a horizontal bearing flange 30. The four carriages are disposed in the machine with their pillars grouped about the center thereof and with their standards extending in pairs forwardly and rearwardly. A lateral bracket 31 is bolted as at 31a, to the flange of each standard, and each bracket and its associated pillar carries a vertical adjustable post 32, each section of the heel and toe wipers being supported upon a pair of these posts. The end posts of the pairs are threaded through the brackets 31 and locked in adjusted position by set-nuts 33, and the side posts are threaded into the pillars and locked in adjusted position by set-nuts 34, as shown in Figs. 3 and 4. Each section of the heel and toe wipers is connected to its pair of posts by ball-joints to permit it to be tilted longitudinally toward its outer end to an appropriate angle to conform to the top surface of the last and properly engage the welt. For this purpose each post is formed with a ball-top 35 having an interior threaded seat 36 to receive the shank of a screw 37 whose head is formed on its under side with a concave ball-shoulder 38, and the wiper-sections are formed with upper and lower semi-spherical seats 39 and 40, respectively, around their screw-holes to fit the ball-shoulders and ball-tops, the shanks of the screws being reduced to clear the holes in the wipers, as shown in Fig. 4a. When the parts are assembled the posts of any wiper section may be adjusted and the section tilted to adjust it to the angle of the last, and when it is properly positioned its screws are set down tight upon it and lock it on its posts, thus enabling the heel and toe wipers for any style of last to be positioned to conform to the longitudinal contour of the heel and toe portions of different sizes of lasts of that style, as shown by the toe section in Fig. 3 for example. By this construction the sections of the toe-wipers may be tipped downwardly toward their outer ends to correspond to the longitudinal curvature of the foot portion of the sole of the last from the ball to the end of the toe, and the sections of the heel-wipers may be tipped downwardly toward their outer ends to correspond with different inclinations of the heel-seats. The set of wipers for any style of last may include only the sectional heel and toe-wipers, but preferably will include the appropriate side-wipers; as the side-wipers are carried by the sectional wipers they are correspondingly adjusted by the vertical adjustments of the latter and move inwardly and outwardly with them toward and away from lasting position, and as the tilt of the heel and toe-wipers is at the ends of the side-wipers when these parts are operating on the work it is outside or beyond the working points of the side-wipers and the continuity of the wiping surfaces is not affected, as clearly appears in Fig. 2. The side-wipers are adjusted vertically with the sectional wipers, and when the latter are positioned all the wipers remain in proper relation to operate upon the work.
- The carriages for the wipers are movable in right lines longitudinally and transversely of the base-plate 8. The front pillars 28 are slidably mounted on a front cross-carrier 41, and the rear pillars are slidably mounted on a rear-cross carrier 42; the carriers are parallel and formed with longitudinal keyways 43 in their sides in which the inwardly projecting tongues 44 on the standards 29 and on the keeper-plates 45 bolted to the pillars are freely movable to permit the sections of the wipers to move toward and away from each other transversely of the bed-plate. The carriers 41 and 42 are slidably mounted on the longitudinal through-rod 12 to move toward and away from each other parallel with the center of the machine under the action of a right and left hand screw-shaft 46 revolubly mounted in the bearing-block 10 and threaded through the lower portions of the carriers. This shaft is operated by a suitable hand-wheel 47 fixed on its front end.
- To provide a backing for the side-wipers and afford means for centering them to conform to the ball of the last, opposite transversely movable bearer-bars 48 are carried in slide-boxes 49 mounted on the upper ends of posts 50 supported on the upright branches 51 of a yoke 52, which in turn is bolted as at 53 to an upright bracket 54 fixed to the inner end of a slide-strip 55 which is movable in a central slideway 56 extending lengthwise of the base-plate 8 and retained therein by side-keeper plates 57 secured to the base-plate by screws 58. The bars 48 are located at about the median line of the machine between the front and rear wiper-carriers, with their outer ends underlying the side-wipers and connected thereto by pins 59 loosely entering holes 60 in the side-wipers at the line of the ball of the last. As the side-wipers vary in contour for lasts of different styles the bearer-bars 48 are shiftable by moving the slide 55 to appropriate position to enable the pins 59 engaging wipers to centralize them to conform to the ball of the particular last employed. When this position is reached the slide is locked by any suitable lock at its rear end controlled by the operator. In the form of lock mechanism shown in Figs. 3, 8 and 10, a short rock-shaft 61 having an eccentric portion 62 is journaled parallel with the tall of the slide 55 in the ends 63 of a bearing-box 64 which bridges the slideway 56 and has lateral wings 65 riding on the base-plate 8 under the keepers 57. The tall of the slide is provided near its rear end with opposite recesses 66 in its edges, and the box 64 is provided with lugs 67 lying in the recesses so 75

that the box moves with the slide. The shaft 61 carries a handle 68 at its rear end, and the parts are so arranged that when the handle is turned down to the position shown in Fig. 10 the eccentric 62 clamps the tail of the slide between the floor of the slideway and the bearing-box to lock the yoke 52 and its bearer-bars 48 in their desired central position between the wiper-carriers. The handle 68 carries an adjustable stop-screw 69 which abuts against a keeper-plate 57 to prevent the overthrow of the eccentric; when the handle is reversely moved the tail of the slide is released, and the handle can be used to move the slide to its desired position. The bars 48 are vertically adjustable to underlie the side-wipers in line with different elevations of the heel and toe wipers for different lasts; for example, by headed bolts 70 passing through elongated slots 71 in the posts 50 and seating in the branches of the yoke 20 as in Fig. 5. The arms 51 of the yoke are provided with elongated keeper-strips 72 which engage the sides of the posts 50 and hold them in position to prevent them from turning on their bolts 70 when pressure is applied to the side-wipers.

The wiper-carriages are movable on their cross-carriers 41 and 42 to spread the wipers as shown in Fig. 1 to enable the last with its pre-welt upper in place on it to be easily assembled 30 on the last-jack and positioned in the plane of the wipers. For this purpose the upper web 6 of each angle-bar carries a transversely movable slide-table 73 having lower runners 73a slideable in transverse key-ways 74 in the web. Each table 35 has a vertical bearing strip 75 at its outer side through which four headed adjusting-screws 76 are threaded. The screws move blocks 77 which run in short slideways 78 in the table and are held therein by top cross-keepers 79 fixed to the 40 table; the connection between the screws and blocks to permit the former to turn in the latter while moving them on the table may be made by forming the inner ends of the screws with an annular reduced necks 80 which receive the ends 45 of set-screws 81 on the blocks. Each central block is pivoted as at 82 to the inner end of a vertically disposed rectangular plate 83 which extends at an angle lengthwise of the table from about its central portion to one end thereof, and 50 each outer block is connected to the outer end of its associated plate by a compound joint formed by a link 84 pivoted at its ends to these parts, this arrangement permitting the more extended movement of the outer ends of the plates 55 required in the operation of the machine. Each pillar 28 carries a laterally extending frame 85 bolted to it as at 86 and having a horizontally disposed anti-friction roller 87 at its outer end arranged to abut against and run lengthwise on the 60 inner face of its associated plate 83, and each pillar is connected to this plate by a saddle-piece 88 fixed to the frame 85 and having an outer hooked end 89 slidably engaging the outer face of the plate, so that as the screws 76 are rotated in one 65 direction they push the plates and wiper-carriages inwardly and when oppositely turned they pull these parts outwardly.

Each table 73 is operated by a toggle-lever 90 which is pivoted at its outer end to the underside 70 of the web 6 and at its inner end to a depending ear 91 on the inner side of the table. By pulling the levers down the tables are moved outwardly to spread the wipers to their extreme open position, and by pushing the levers up the tables are moved inwardly to retract the wipers toward the

center of the machine to underlie the welt as in Fig. 7. The toggle-levers are operated by depending push and pull links 92 whose lower ends are suitably connected to a common vertically movable handle-bar or foot-treadle arranged below the work-table on which the machine rests and constructed to hold the toggle-levers in either of their positions. 5

The last-jack 93 is pivoted at its lower end to the inner end of an arm 94 which is carried at 10 its rear end on a short cross-shaft 95 mounted in a pair of uprights 96 on a bearing block 97 which rides on the keeper-strips 57 and is bolted as at 98 to the carrier 42 to move with the latter, so that when the carrier positions the wipers the 15 jack is automatically positioned in association with them, the block being cut-away to provide clearance for the shaft 46 as shown in Fig. 3. The jack is normally held in its vertical position against a shoulder 99 on the arm 94 as shown in 20 Figs. 3 and 16 by a leaf-spring 100 fixed at its upper end to the jack and bearing at its free end against the curved end of the arm, the arrangement being such that the jack can be rocked back and forth on its arm to a limited extent to 25 bring its pin to position to engage the usual jack-holes in lasts of different dimensions and when the last is mounted on the jack the latter is swung to its normal operative position where it is held by the leaf-spring. The arm 94 is curved upward- 30 to conform and rest upon an eccentric 101 carried by a short cross-shaft 102 which is journaled in the uprights 96 and extends at one end beyond an upright where it is provided with a ratchet-surface 103 and with an upwardly ex- 35 tending hand-lever 104. A pawl 105 is pivotally mounted on the outer end of the upright in position to engage the ratchet and is normally held in position thereon by a cam-heel 106 on the inner end of a short lever 107 which is pivoted 40 as at 108 at its lower end to the upright and is held in position to engage and maintain the pawl in its normal position against the ratchet by a coil-spring 109 attached at its end to pins 110 and 111 fixed respectively on the upright and a lower 45 arm 112 of the lever 107. A release pin 113 is set in the lever 107 in position to wipe against the end of the pawl 105 and cam the latter away from the ratchet when the lever is moved inwardly, so that the shaft 102 is released and 50 the hand-lever 104 can be rocked forward to permit the arm 94 and the last-jack 93 to be moved to their lowered position shown in Fig. 3 which they occupy when the last is to be positioned on or removed from the jack. When the last with 55 the shoe-upper in place on it is put on the jack and the hand-lever 104 is rocked rearwardly the eccentric 101 raises the last and shoe-upper to working position in the plane of the wipers where they are automatically locked and maintained 60 by the engagement of the pawl 105 with the ratchet 103 until the lasting operation is completed; then the release lever 107 is again moved inwardly to release the pawl and permit the lever 104 to be moved inwardly to lower the jack to the 65 position shown in Fig. 3.

A screw-press comprising a pair of swinging arms 115 and 116 rotatably carried on a standard 70 117 is mounted on the work-table adjacent the machine as shown in Fig. 11. A screw-shaft 118 having an operating handle 119 and a flyweight at its upper end is threaded through a bearing 120 on the extensible end of each arm; the screw on the arm 115 carries a flat presser-head 121 and the screw on the arm 116 carries a presser- 75

head 122 having a contour to fit the toe of the last, the heads being connected to the arms by ball-joints 123 whereby the screws can be rotated to apply pressure while the heads are seated on their work. The head 121 is used to shape the outer-sole 114 to the last with a mold-block 124 composed of a flat piece of wood conforming to the general shape of the lasts and a lining 125 of hard rubber shaped on its lower surface to form the tread of the outer-sole of the finished shoe. The head 121 itself may be formed to fit the sole to the last and form the mold.

In setting the lasting machine a set of wiper plates corresponding in form with the style of the lasts to be used are positioned loosely on the posts 32, which are adjusted to set the heel and toe wipers in proper positions and angles to conform to their associated portions of the last, and the screws 37 are set down to lock the wipers in place on their posts. The yoke 52 is set and locked in position so that its bars 48 will position the sidewipers to centralize the latter to conform to the ball of the lasts to be used. The wipers now will serve all sizes and widths of the same form or style of last, so that the operation of the machine need not be stopped for changes in their sizes or widths.

By operating the shaft 46 the wipers may be adjusted to fit lasts of different sizes of the desired style, and by operating the screws 76 the wipers may be adjusted outwardly for greater widths and inwardly for lesser widths of lasts of different sizes or lengths in that style. As the wiper carriages move bodily toward and away from each other in both their longitudinal and lateral movements, the assembled wipers open and close in straight alinement and so conform in their positions during the lasting operations with the contour of the selected style of the last in its various sizes and widths, and the lasting unit presents to the work a continuous working edge without any gaps between its members. Also, by operating the screws 76 the angle or pitch of the plates 83 to the carriages may be varied to set the wipers for different gradings of shoes.

In using the machine the tables 73 are spread and the wipers are expanded by turning the handwheel 47 contraclockwise, and a last of the chosen size and width with the shoe-upper and its welt in its initial position thereon is mounted on the last-jack, the lever 104 is operated to raise the last up and bring the edge of the shoe-upper and welt into the plane of the wipers, where these parts are locked by the ratchet. The work comes to the machine with the welt temporarily tacked to the last at its toe and sides, and the insole with its cork-filler temporarily tacked to the last at its heel and toe. The tables 73 are now moved inwardly to position the wipers under the welt as indicated in Fig. 7, and the tacks for the welt are pulled; if, as sometimes happens, the toe portion of the last projects above its proper working position in the upper the press-head 122 is swung into position above the toe of the last as approximately shown by the dotted line position at the left in Fig. 11 and operated to press the last to place in the upper. Then the hand-wheel 47 is rotated clockwise to move the wipers inwardly to their closed position shown in Fig. 2 to pull the upper taut upon the body of the last and wipe the edge of the shoe-upper and the inner portion of the welt onto the insole on the last, these parts being wiped up snug against the cork-filler as indicated in Fig. 15. The

head 122, if it has been used, is now released and swung back to its full line position in Fig. 11, the insole tacks are pulled, the insole and welt are wiped with cement, the outersole 114 with its heel piece wiped with cement is applied to the work, the mold-block 124 is placed on the outer-sole, and the press-head 121 is swung into position above the block, as indicated by the dotted lines at the left of Fig. 11, and its screw is operated to press the outer-sole upon the inner-sole and welt and hold these parts together during the brief interval required for the cement to dry. After the cement sets the head 121 and block are released, and the wipers are withdrawn from the work by turning the hand-wheel 47 contraclockwise, and the tables 73 are spread to their outer positions; the last with the shoe parts is removed, and another last with its upper and welt is mounted on the jack, and the operations are repeated.

The two-point support of each section of the heel and toe wipers afforded by its pair of rigid posts 32, and the three-point support of each side-wiper afforded by its seating at its ends on the associated wipers and at its center on its supporting-bar 48 enable the wipers to provide a rigid bed for the work while under the stress and pressure of the press, and prevent displacement or distortion of the wipers thereby. When the mold presses the adhesive outer-sole into union with the upper it also shapes or molds this sole to fit the bottom of the last, thereby eliminating the use of the usual separate sole-molding machine; also, the mold and last perform the function of the usual separate welt-beating machine; my invention eliminates the use of these machines with their additional operators.

In practice, a pair of these machines is mounted on the work-table with the press located between them, one of the machines being provided with wipers for a right-foot last and the other with wipers for a left-foot last, as shown in Fig. 11. By this organization one operator can attend to two lasting machines. The lasting operation can be carried out upon (say) the left-foot machine of Fig. 11 and the head 121 of the press applied to the outer sole of the work upon it. While the sole is under pressure and setting on the first machine, the operator can similarly last another upper in the second (right-foot) machine of Fig. 11, the head 122 now being used if necessary in the right-hand dotted line position in Fig. 11 in the same way as before, and when the work is finished, he may apply the pressure-head 121 to the outer sole in the second machine, and while this sole is under pressure and setting he may remove the last and work from the first machine and perform another lasting operation upon it.

It is obvious that my present invention may be used for lasting not only pre-welt uppers, but also for well known McKay, turn, and regular methods of lasting.

I claim:

1. In a lasting machine, a pair of heel-wipers having a tongue and open-top groove connection, a pair of toe-wipers having a tongue and open-top groove connection, a pair of side-wipers each having a tongue and open-top groove connection at one end with one of the heel-wipers and at its other end with one of the toe-wipers, the joints between the wipers being formed with flush surfaces, and angular connections between each side-wiper and its associated heel and toe wipers.

2. In a lasting machine, a pair of heel-wipers, a pair of toe-wipers, a pair of side-wipers carried at their ends on wipers of the other pairs and having cam-slots near their ends, and headed studs on the toe and heel wipers engaging the slots. 5
3. In a lasting machine, a pair of heel-wipers having a slip joint, a pair of toe-wipers having a slip joint, a pair of side-wipers each having slip-joints with wipers of the other pairs, the joints of the wipers being formed with flush surfaces, and connections between each side wiper and its associated wipers to hold it thereon. 10
4. In a lasting machine, an opposite pair of plates forming a heel-wiper, one of said plates having a tongue and the other an open-top groove to receive said tongue, an opposite pair of plates forming a toe-wiper, one of said plates having a tongue and the other an open-top groove to receive said tongue, each of said plates having a second open-top groove extending at an angle to its said first groove, an opposite pair of elongated plates forming side-wipers and each having its ends formed to enter the angular groove in one of said heel-plates and in one of said toe-plates, each of said side-wipers having cam-slots near its ends, and studs on the plates of the heel and toe wipers running in said slots. 15
5. In a lasting machine, a base having an opposite pair of through-rod, a pair of carriers slidably carried on said rods, a right and left screw shaft on the base engaging the carriers to move them inwardly toward each other and outwardly away from each other, a pair of wiper-carriages slidably mounted on each carrier, a toe-wiper plate carried by each carriage on one of the carriers, a heel wiper-plate carried by each carriage on the other carrier, side-wipers carried at their ends on the heel and toe plates, and slot-and-pin connections between each side-wiper and its supporting wipers constructed to close the side wipers when the carriers move inwardly and to open them when the carriers move outwardly. 20
6. In a lasting machine, a frame having a rectangular base-plate and horizontal upper side webs, a pair of carriers movable along the plate toward and away from its center, wiper-carriages movable on said carriers transversely of the plate, a set of heel, toe and side wipers on the carriers, a table slidably mounted on each upper web, and having four transverse slideways, four adjusting screws having threaded engagement with each table; a block sliding in each transverse way and engaged by an adjusting screw, a vertical plate at the side of each wiper-carriage, a horizontal roller and a saddle on each carriage abutting against the opposite faces of the associated plate, and pivotal connections between the ends of each plate and its pair of the adjusting screws. 25
7. In a lasting-machine, a pair of wiper carriers, means to move the carriers toward and away from each other, a pair of wiper carriages movably mounted on each carrier, an angular guide plate for each carriage, and means to adjust the pitch of each plate to its associated carriage. 30
8. In a lasting machine, a sectional toe-wiper, a sectional heel-wiper, opposite carriages for the sections of the toe-wiper, opposite carriages for the sections of the heel-wiper, each wiper-section having post holes, each carriage having posts to engage holes in its associated wiper-section, and means to adjust the carriages to position the posts to engage the holes of the wipers in their lasting position. 35
9. In a lasting machine, a wiper-carriage having a pair of posts each formed with a ball-top and having a threaded-seat in said top, screws each having a shank engaging a seat and having a head with a concave under surface, and a wiper-plate having holes to loosely receive said shanks and semi-spherical seats around each hole to fit the ball-top of a post and the concave under surface of a screw-head. 5
10. In a lasting machine, a sectional wiper, 10 opposite carriages for the wiper sections, and universal couplings between each carriage and its associated wiper section to lock the section in different adjustments. 15
11. In a lasting machine, a base, side wipers having central holes, a yoke movable on the base, a pair of opposite uprights adjustably mounted on the arms of the yoke, transverse slide-boxes on the uprights, bearer-bars in the boxes, and pins on the inner ends of the bars to engage the 20 holes in the wipers. 25
12. In a lasting machine, a base having a slide-way, a strip moveable in the slideway, a yoke on the strip carrying slide-boxes at its upper ends, bearer-bars movable in said boxes, pins on said bars, a pair of side-wipers having holes for said pins in their central portions, and means to lock said strip in position to centralize said wipers to conform to the ball of the last employed. 30
13. In a lasting machine, a base having a slide-way, a strip moveable in the slideway, a yoke on the strip carrying slide-boxes at its upper ends, bearer-bars movable in said boxes, pins on said bars, a pair of side-wipers having holes for said pins in their central portions, and a bearing-box 35 on the rear end of said strip, a rock-shaft journaled in said bearing-box parallel with said strip and having an eccentric portion adapted to engage the strip, and a handle on said rock-shaft. 35
14. In a lasting machine, a movable wiper-carrier, a bearing-block connected to the carrier, an arm pivoted at one end on said block and having its free-end formed with a curved face and a rear shoulder, a last-jack pivoted to the free-end of said arm in position to abut against said shoulder, and a leaf-spring fixed to the jack and having its free end bearing on said face. 40
15. In a lasting machine, a base, a heel-wiper carrier and a connected bearing-block carried 45 on said base, an eccentric rock-shaft journaled in said block, an arm pivoted at its outer end on said block and bearing on said eccentric, a last-jack pivoted on the inner end of said arm, a ratchet on said shaft, a pawl pivoted on said block in position to engage the ratchet, a spring-stressed lever pivoted on said block and engaging said pawl to hold the latter against the ratchet in the normal position of the lever, a pin on said lever to release the pawl when the lever is moved against the stress of its spring, and a lever on 50 said rock-shaft. 55
16. In a lasting machine, a base, a wiper-carrier movable on said base, a bearing-block movable on said base and connected at its inner end to said carrier, a last-jack, an arm carrying the jack and pivotally mounted on said block, a shaft journaled in said block and having an eccentric underlying said arm and a ratchet adjacent the eccentric, a pawl pivoted on said block in the line 70 of the ratchet, a lever on the shaft, and a lever pivoted on the bearing in rear of the shaft and constructed to hold the pawl against the ratchet when in one position and to release the pawl when in another position. 75

17. In a lasting machine, a set of heel, toe and side wipers having slip-joints, carriages for said wipers, a pair of carriers transverse to and supporting said carriages, means to move said carriages on the carriers into and out of position in which the wipers underlie the welt of a shoe-upper, and means including a right and left screw shaft and angular guides to move the carriers and carriages respectively and the wipers into and out of position to last the upper. 5
18. In a lasting machine, a pair of interconnecting heel wipers, a pair of interconnecting toe wipers, a pair of side wipers movably mounted on the heel and toe wipers, pin and slot connections between each side wiper and its supporting wipers, said wipers being formed with flush joints at their interconnecting portions. 10
19. Means for lasting and soleing shoes comprising a set of heel, toe and side wipers, forming a continuous last-opening, a last-jack, mechanism to move the wipers to and away from position adjoining an upper on a last on the jack, 15
20. Means for lasting and soleing shoes comprising a spaced pair of lasting machines each having a set of heel, toe and side wipers having flush joints, a last-jack and mechanism to simultaneously move its set of wipers to and away from lasting position, a press intermediate said lasting machines having a swinging arm constructed to swing above each of said machines, a screw-shaft threaded through said arm, a sole-shaping mold actuated by the shaft and having its face formed of corresponding size and contour as an outer-sole to fit the latter to the bottom of a last on the jack. 20

JOSEPH W. BARNA.
